DESIGN FOR A SLEET SCRAPER

Martin E. Trolle, St. Paul, Minn., assignor to
Brown & Bigelow, St. Paul, Minn., a corpora-
tion of Minnesota

Application November 21, 1941, Serial No. 104,237

Term of patent 14 years

To all whom it may concern:

Be it known that I, Martin E. Trolle, a citizen of the United States, residing at St. Paul, county of Ramsey, and State of Minnesota, have invented a new, original, and ornamental Design for a Sleet Scraper, of which the following is a specification, reference being had to the accompanying drawing, forming part thereof.

Figure 1 is a side elevational view of a sleet scraper, showing my new design.

Figure 2 is a side elevational view thereof from the opposite side of Figure 1.

Figure 3 is an edge elevational view thereof.

Figure 4 is a bottom edge view thereof.

I claim:

The ornamental design for a sleet scraper, as shown.

MARTIN E. TROLLEN.
